UNITED STATES PATENT OFFICE.

ARTHUR R. BULLOCK, OF CLEVELAND, OHIO, ASSIGNOR TO BENJAMIN PARMELY, JR., OF CLEVELAND, OHIO.

GAS-PRESSURE-REDUCING APPARATUS.

SPECIFICATION forming part of Letters Patent No. 728,361, dated May 19, 1903.

Application filed July 13, 1899. Serial No. 723,676. (No model.)

To all whom it may concern:

Be it known that I, ARTHUR R. BULLOCK, a citizen of the United States of America, and a resident of Cleveland, in the county of Cuyahoga and State of Ohio, have invented certain new and useful Improvements in Gas-Pressure-Reducing Apparatus, of which the following is a specification.

This invention relates to contrivances for controlling the gas pressure or pressures between gas-generators and the points or places of or for consumption of gas; and the object of my invention is to provide an apparatus wherein and whereby a predetermined pressure may be maintained for or at the terminals of consumption of gas regardless of fluctuations in the supply of gas to the pressure-regulator as well as an irregular consumption of gas therefrom. I attain this object in and by an apparatus constructed and equipped substantially in the manner as shown in the accompanying drawings, in which—

Figure 1 is a central vertical sectional view of a pressure-regulator; and Fig. 2 is a horizontal sectional view of the same, taken on the line $\alpha\alpha$ of Fig. 1.

Like letters of reference denote like parts in the drawings and specification.

The vessel A constitutes the chief element of the apparatus, being preferably of a cylindrical form and of greater depth than width. Said vessel is provided at a suitable point intermediate its top and bottom with a horizontally-extending diaphragm a , provided with a central opening of a size corresponding with the diameter of a tube b , depending from the under side of said diaphragm, said tube having open ends, as shown, thereby providing a point of communication between the space above and below said diaphragm.

From or through the top c of the vessel A extends vertically a flue e , having its top provided with a contracted opening or outlet f , its lower end being open throughout its diameter. As shown, said flue preferably extends to a point below the bottom of the tube b . The flue e is secured relatively to the vessel in any suitable manner.

It will be readily understood from the above that the vessel is divided into two compartments, one upper, (designated as j .) the other lower (designated as l .) said compartments being in communication through the tube b , 55 and, furthermore, that a third compartment is provided by the flue e , this compartment and the lower compartment l being in communication through the open end of the said flue.

i designates an opening below the diaphragm a through the walls of the vessel and forming a means for connecting the lower compartment with a gas-generating apparatus.

h designates an opening or vent formed in the top c of the vessel, said vent permitting the upper compartment to be subject to the atmospheric pressure.

Each of the several compartments is intended to receive suitable liquid, such as water, and preferably the level thereof is at a point in each compartment where the compartment will be filled to practically one-half its capacity, and thereby providing pressure-chambers in the compartment l and flue e , respectively, under the control of the gas and a chamber in the upper compartment subject to the atmospheric pressure.

In providing a communicating port between 80 the chamber in the lower compartment and that within the flue e for the passage of the gas, which is of an extremely-sensitive nature and which will be effective, is the main feature of the present invention, inasmuch as upon such port or passage-way depends the efficiency of the pressure-regulator. This port is preferably formed or provided as follows:

Within the lower compartment l is located 90 an annular float E , carrying one end of a pipe F , the end preferably extending above the upper surface of the float, said pipe having its other end carried inwardly and upwardly within the flue e and terminating in a 95 downwardly-extending portion, the whole being of S form, both ends of the pipe being open. The bends of the pipe are arranged so as to permit of a vertical movement of the float E . Located in the upper compartment 100

is a float C, carrying arms which extend downwardly and inwardly into the flue e and adapted to support a cup D, which is located within the flue e and movable vertically therein correspondingly with the movement of the float C. The said cup D is adapted to contain liquid, and the free inner end of the pipe F extends therein, as shown. None of these parts necessarily come in contact, and hence there is no liability of the parts becoming useless through wear, &c.

It will now be understood that with a gas-inlet at i and a gas-outlet at f any increase of pressure in the chamber of the lower compartment will force the liquid in the vessel to rise in the upper compartment, while the water-level in the lower compartment will be lowered. This movement affects both floats, the float C rising, carrying with it the cup D, while the float E is lowered, lowering the end of the pipe F within the cup D, with the result that the liquid column at the end of the pipe F is increased in height and increasing the resistance to the passage of the gas. As soon as the pressure in the chamber at the top of the flue e is decreased (such pressure being primarily the cause of the movement just described) the height of the column of liquid in such flue is permitted to rise, lowering the level of the liquid in the upper compartment, and thereby permitting the cup D to descend and decreasing the resistance at the end of the pipe F, which in turn relieves the pressure in the lower compartment, causing the float E to rise and raising the pipe F and further decreasing the resistance at the outlet end of the pipe F. It will therefore be obvious that a liquid-check is formed at the end of the pipe F, the pressure of which is automatically controlled by the movements of the floats C and E, the latter having their movements by reason of the differences in pressure between the chambers in the lower compartment and the flue e, and the movements of the pipe F and cup D being in opposing directions it will be understood that the said check is exceedingly sensitive in character and of a form to be reliable in operation. As an increase of pressure in the inlet end of the pipe F is counteracted by an increased liquid-check, and vice versa, the construction is simple and efficient in operation and durable in structure.

m designates a pipe located in the pipe F, said pipe m having its upper end above the upper end of the pipe F to permit, if desired, the attachment of a suitable pipe inserted through the opening i, by means of which a siphoning action can be had with the interior of the regulator.

It will be understood that a simple and efficient regulator extremely sensitive in its action and free from tendencies which would cause the parts to become worn is provided and one which is especially applicable to the control of the passage of acetylene gas to the burners.

Having thus described my invention, what I claim as new is—

1. A liquid-controlled gas-pressure-reducing apparatus comprising a vessel having a diaphragm with a depending tube; a flue extending through said tube and communicating with the lower compartment; floats in the compartments formed by said diaphragm; and a gas passage-way leading from the lower compartment to the said flue, said passage-way having its outlet subjected to liquid-pressure controlled by the movement of said floats. 70

2. A liquid-controlled gas-pressure-reducing apparatus comprising a vessel having a diaphragm with a depending tube; a flue extending through said tube and communicating with the lower compartment; floats in the compartments formed by said diaphragm; a gas passage-way carried by the lower float and leading from the lower compartment to the said flue; and means carried by the upper float for subjecting the outlet end of said passage-way to liquid-pressure, the latter being regulated by the relative movement of the floats. 80

3. A liquid-controlled gas-pressure-reducing apparatus comprising a vessel having a diaphragm with a depending tube; a flue extending through said tube and communicating with the lower compartment; floats in the compartments formed by said diaphragm; and a sectional gas passage-way connecting said lower compartment and the flue, the sections being carried by the said floats, said passage-way having a variable liquid-resistance controlled by the movements of said floats. 90

4. A liquid-controlled gas-pressure-reducing apparatus comprising a vessel having a diaphragm with depending tube; a flue extending through said tube; floats in the compartments formed by said diaphragm; a cup within said flue carried by the upper float; and a pipe suspended by the lower float, the said pipe or conduit having one terminal in open relation with the gas-containing portion of said vessel and another terminal under a seal of liquid within said cup, substantially as described. 100

5. A hydrostatically-controlled gas-pressure-reducing apparatus comprising a vessel, a diaphragm with depending tube in the lower portion of said vessel, a flue extending through said tube, a liquid-filled cup carried by a medium floating above said diaphragm, and a pipe supported by a medium floating below said diaphragm, the said pipe extending from the gas-supply chamber into said cup, substantially as described. 110

Signed by me at Cleveland, Ohio, this 12th day of June, 1899.

ARTHUR R. BULLOCK.
